NECK RING AND SEAL FOR NURSING UNITS

Adda M. Allen, Arlington, Va., assignor to Disposable Bottle Corporation, Washington, D. C., a corporation of Delaware

Application August 29, 1947, Serial No. 771,329

7 Claims. (Cl. 215—11)

1

The present invention relates to nursing units of a type which have only recently gone into practical use. The general type of nursing unit referred to comprises a relatively narrow collar of rigid material and a container of thin, pliant, retractile, disposable material having an open end adapted for sealing connection with the collar. As disclosed in my copending application Serial No. 560,610, filed October 27, 1944, which issued as Patent No. 2,446,451, dated August 3, 1948, the collar of the nursing unit comprises two concentric parts consisting of a neck portion to which the nipple is attached and a retaining ring portion, said concentric parts having cooperating means to clamp them one against the other to retain the open end of the container in sealing engagement between the parts. The nipple, which may be of conventional type, is attached to the neck portion but is of a diameter somewhat less than that of the collar and is spaced a substantial distance inwardly from the outer edge of the collar, the front face of the collar being tapered steeply inwardly to the point where the nipple is connected, the resulting construction being such that it will permit the nipple to be tilted inwardly at a steep angle toward the infant's mouth. In the copending application referred to, the container for the milk or formula is described as being of pliant material such as to have its shape altered by the presence of liquid therein, and the container is described as being of such design and to have such capacity as to assume a length somewhat greater than the width of the collar, whereby the unit is mainly supported on a surface by the filled and pliable container. During nursing with a unit of the type referred to, as described in the said copending application, the thin material of the container retracts toward and into the collar as the infant nurses, the collar being of diameter great enough to permit substantially all of the material of the container to retract into the collar without interfering with the flow of the formula through the nipple.

The present invention is an improvement in the general type of nursing unit as described in said earlier application, the features of improvement being mainly concerned with the manner in which the open end of the container is sealed in the collar. A principal object of the invention is to provide a design of nursing unit of the type referred to, wherein a positive and effective seal of the open end of the container is provided, said seal being self-protecting against contact with the contents of the container, the

2

number of parts of the unit being reduced to a minimum.

It is also an object of the invention to accomplish the above purposes with a combination of parts which lend themselves to rapid and convenient manipulation, and which parts are of such simple design that they may be kept clean and sterile. As stated, the most important feature of improvement in the present application is in the cooperation of parts which effect the sealing off of the open end of the container. In the copending application referred to, one of the cooperating parts is disclosed provided with a sealing gasket, whereby the open end of the container is effectively gripped between the cooperating parts of the collar. An early variation of the same general development is disclosed in another of my copending applications, Serial No. 526,354, filed March 14, 1944, which issued as Patent No. 2,448,569, dated September 7, 1948.

Since the date of the early developments of my copending applications, as referred to above, various designs of nursing units of the same general character have been developed, and one of the problems which has been given considerable attention is that of sealing the open end of the container in a leakproof manner. For example, one subsequent development comprises an inside neck portion having a nipple-attaching bead and an exterior groove into which a separate gasket member is adapted to be pressed by a retaining ring portion of the collar which is in the form of a skirt threaded to the neck portion, the skirt bearing against a gasket ring when threaded onto the neck portion in order to press the gasket into the groove in the neck portion to seal the open end of the container which is previously placed over and around the outside surface of the neck portion and over the groove therein. Such a variation of my early developments, as disclosed in the copending applications referred to, was not entirely successful, particularly due to difficulties concerned with the sealing of the open end of the container.

A subsequent improvement of the same type which has been developed for commercial use comprises a collar of the same type consisting of the neck portion and retaining ring portion, these two portions being clamped together by a snapping action rather than a threaded or turning action. In this development, the neck portion has a depending skirt with a groove in the exterior wall thereof, the open end of the container is placed around this skirt, and a separate annular gasket is then placed around the skirt

and the container to hold the container against the skirt. Thereafter, an annular retaining ring portion is forced over the skirt in a direction axially of the container, this retaining ring portion having a reduced inside surface which engages the gasket and forces it into tight sealing relation in the groove in the skirt against the open end of the container.

The present invention is a further refinement in the chain of developments just described.

In the drawings:

Figure 1 is a perspective view of the various elements which form the nursing unit, showing them separated from one another but arranged in the manner in which they would be assembled;

Figure 2 is a side elevational view of the nursing unit after the elements shown in Figure 1 have been assembled;

Figure 3 is a horizontal sectional view taken along the line 3-3 of Figure 2;

Figure 4 is a central vertical sectional view through the retaining ring portion of the nursing unit and through the circular gasket which is carried thereby;

Figure 5 is a central vertical sectional view through the neck portion of the collar;

Figures 6, 7, and 8 are views which show successive positions of the retaining ring with respect to the neck portion when the former is being clamped against the latter to seal the open end of the container between the two portions.

In these views, the retaining ring is shown in vertical section, and the container is illustrated broken away in order to more clearly expose the parts. In Figure 6, the gasket 30 is shown contacting the leading side of the bead 20 with respect to the relative movement of the two concentric rings when clamping the container in sealed position, and in Figure 7, the gasket 30 is shown contacting the trailing side of the bead 20 with respect to the said relative movement of the two concentric rings.

Figures 9 and 10 are partial sectional views similar to Figure 4, but showing modifications of the retaining ring structure.

I will not describe the container employed with the present invention in any great detail, as it is now well-known in the art and has been disclosed in certain of my previous applications, including those referred to above. The material employed for the container may be of any satisfactory commercial material which is thin, pliable, preferably transparent, and retractile, in order to perform during nursing in the manner described in this and earlier applications referred to. Of course, the material must be strong and tough enough to stand the use to which it is being put. I have found one acceptable material which is known as "polyethylene," a film-like material, transparent, on the order of .002 inch in thickness, capable of retracting into the collar as the contents of the container are being withdrawn by nursing action, so that the nursing unit will be self-lactating. This material is of such thinness that its form is distorted by the liquid contents and it will assume the shape of the surface on which it rests, as previously mentioned. When the container is filled, it may be pressed by the fingers to initially expel air prior to nursing, and to assist the discharge of the formula through the nipple in the case of difficult feeders. An acceptable material is that which is described in my copending application Serial No. 717,105, filed December 19, 1946, the disclosure of said application with respect to the

material being made a part hereof by reference. A general disclosure of this acceptable film material for the container appears in "Modern Packaging" of September 1946, pages 130-134 and 166, 168, the article referred to having been written by Dr. J. W. Shackleton of the E. I. duPont de Nemours & Co.

Referring to Figure 2, the three principal elements of the outfit are the nipple N, the collar R, and the container C. Referring to Figure 1, the collar consists of a neck portion K and a retaining ring portion I, these portions being appropriately designed to be clamped to one another and to seal the open end of the container therebetween. It will be understood that the container is open at its upper end as shown in Figure 1, prior to assembly, but is closed at its lower end by a sealing line or band as shown in Figure 1 and now well-known in the art.

Referring to Figure 5, the neck portion K comprises a body flange 10, circular in outline, which tapers relatively steeply inwardly on its forward face to a short central tubular extension 14 which terminates in a nipple attaching bead 16 over which the nipple N can be stretched. The rear side of the flange 10 is provided with a depending skirt 18, which has a protruding annular bead 20 on its exterior surface located substantially centrally of the longitudinal length of the skirt. There is a central bore 22 through the tubular extension 14, and this leads from the hollow interior 24 formed by the skirt 18, the interior surface being smooth throughout and rounded to completely eliminate any crevices, whereby cleaning of the exposed surfaces is facilitated.

The clamping ring I is of substantially cylindrical form having an inside surface or bore 26 which is somewhat greater than the exterior diameter of the skirt 18. Located near the middle of the axial length of the neck ring is an annular inside groove 28, and in this groove an annular gasket ring 30 of rubber or the like is adapted to be placed. It will be understood that while the gasket ring 30 may be removed from the groove 28 during cleaning of the ring I, in general, this gasket will be kept in place in its groove, and thus in effect will be a part of the retaining ring when the nursing unit is manipulated in use.

It will be observed from Figure 4 that the cross-sectional thickness of the gasket ring 30 is greater than the depth of the groove 28. In fact, the thickness of the gasket ring is substantially twice the lateral depth of the groove 28 as viewed in Figure 4. The dimensions of the parts are relatively coordinated in such manner that while the exterior diameter of the gasket ring is substantially equal to that of the axial wall of the groove 28, the interior diameter of the gasket ring is somewhat less than the exterior diameter of the bead 20 on the skirt 18. Therefore, when the parts of the collar are assembled or clamped to one another as portrayed in Figures 6-8, the gasket 30 will be distorted in passing over the bead 20 and will be maintained in distorted condition to exert a sealing force against the open end of the container. The arrangement of the parts is such that a sealing pressure will be stored up in the material of the gasket itself, and this pressure will be exerted against the bead 20 to insure a very tight and positive seal.

Referring to Figure 4, it will be observed that the inner and outer surfaces of the annular groove 28 are slightly undercut with respect to the inside surface 26 of the clamping ring,

whereby inner and outer spaces are provided into which the distorted material of the gasket 30 may expand as it moves over the bead 20.

For example, referring to Figure 6, the ring I is shown in its initial position as it is placed around the skirt 18 just before the parts are clamped together. It will be understood that the open end of the container C has already been wrapped around the skirt 18, and to facilitate locking the parts together, the closed end of the container C is pushed upwardly within the chamber 24 of the neck portion. As is apparent from Figure 6, the relative diameters of gasket 30 and bead 20 are such that it would be difficult to force the ring I home to clamping position (that of Figure 7) without the application of considerable force. In order to provide operation which does not require great force, and yet which will afford a tight enough seal, I have designed the parts with the relative dimensions as generally illustrated, but with the annular groove 28 of such design that it will provide room for expansion of the gasket 30 at necessary times when said gasket is passing over the most critical dimension of the bead 20. In Figure 6, the undercut design of the groove 28 provides an inner expansion chamber 32 and an outer expansion chamber 34. When initial pressure is applied with the parts in the condition shown in Figure 6, the gasket 30 can expand into the space 32, thus permitting the ring I to move to its fully clamped position of Figure 7, the gasket riding over the enlargement or bead 20 on the skirt of the neck portion. When the parts have been clamped together as in Figure 7, it will be noted that the outer surface of the ring I is in contact with the inner face of the flange 10 of the neck portion, but the annular groove 28 is so positioned with respect to the bead 20 that in this position of the parts, the gasket 30 still remains distorted and exerts a force inwardly against the surface of the skirt 18 and against the bead 20 to effectively seal the container C against the neck ring. The gasket 30 thus acts to hold a tight seal by its own inherent tendency to assume its natural shape, being held partially expanded by the bead 20 when in the condition of Figure 7, and the gasket is positively compressed against the upper surface of the bead 20 and against the upper surface of the skirt 18 by the inner lower edge of the neck ring I just above the groove 28.

If desired, the outer end of the groove 28 may be undercut, as previously mentioned, to provide an expansion chamber 34 which may function in substantially the same way to receive the distorted mass of material of the gasket when the ring I is being removed from the skirt 18 as indicated in Figure 8. It would be possible, of course, to design the groove 28 in such form that one expansion chamber would provide the necessary relief in both clamping and unclamping movements of the ring I.

It will be obvious that dimensions for the parts may be varied somewhat in the practice of this invention. However, I have found that dimensions as illustrated in the drawings are satisfactory in operation, the drawings being to exact size. It will be noted, however, that certain relative dimensions are important, such as the distance of the bead 20 from the lower face of the flange 10 of the neck portion, and the corresponding location of the groove 28 and the gasket 30 in the ring I at an appropriate distance inwardly from the outer end of the ring I. These

dimensions are important in that the neck ring I should be stopped in its clamping movement by the flange 10 prior to the time when the gasket 30 would obtain complete relief. Because of this important relative arrangement of the parts, the gasket 30 is still under stress when the parts are locked together as in Figure 7, and the stored up energy in the gasket exerts a continuous sealing pressure against the open end of

10 the container. In connection with the dimensions to be chosen, they should be such as to provide as tight a seal as possible without making necessary the application of undue force in clamping the parts together. In this connection, I have found that when using container material of the type referred to, which is of smooth character, the material itself serves to lubricate the passage of gasket 30 over the bead 20 from the position 15 of Figure 6 to that of Figure 7. In fact, I have found that, with parts of the dimensions shown, the clamping action cannot be conveniently accomplished even when great pressure is exerted between the parts, if the film container is not present. However, when present, as indicated in 20 Figure 6, a moderate pressing of parts K and I toward one another, with a slight relatively rotary motion between them will cause the gasket to pass over the bead 20, with convenient ease, yet 25 when in the position of Figure 7, a very tight seal is had. In fact, the seal is so tight that it is difficult to draw the parts away from one another even upon exerting great force, unless they are given a combined turning and pulling action of 30 35 the type just mentioned, lubricated by the film container.

Figures 9 and 10 are illustrative of variations of design of the sealing groove 28 which may provide a similar action. In Figure 9, the groove 40 is shown as being substantially rectangular in form, providing inner and outer pockets 42 and 44. In Figure 10, the groove is shown as elliptical in contour, providing inner and outer pockets 46 and 48. In each case, the lateral depth 45 of the groove is substantially less than the thickness of the ring 30, and in carrying out the design which I have in practical use, it is found that successful operation results when the depth of the groove is approximately equal to the radius 50 of the cross-section of the gasket 30.

The operation of the device will be clear from the above description, and reference to the earlier applications referred to. The sterile container C is wrapped around the skirt of the neck portion 55 K and then the parts are clamped as illustrated in Figures 6-8. Thereafter, the container is filled through the opening 22 and the nipple is then applied over the bead 16. The unit is then in condition for use, and after use, the parts 60 may be separated and the container C thrown away. The simple neck ring parts obviously can be easily cleaned. It will be observed that the location of the gasket 34 and the annular groove 23 in the clamping ring I is such that these parts 65 are not exposed to the formula. The latter cannot pass upwardly over the bead 20 because of the sealing action of the gasket 34. If necessary, the gasket 34 can be removed from the neck ring I when the parts are cleaned, but this may 70 not be necessary, and for purposes of assembly, the gasket may be considered as a part of the clamping ring.

It will be observed that by reason of the fact that the gasket 34 is in effect a part of the outer 75 of the two concentric rings which form the collar,

the separate step of separately applying the gasket ring to the unit is avoided. By reason of the fact that the gasket is confined in a groove in the outer ring, there is no twisting or undue stretching of this gasket which would tend to impair its efficient operation. It will also be understood that because the gasket is confined in the groove, pressure which is applied to it is so confined as to be transmitted circularly throughout all of the material of the gasket when it is forced over the bead and thus energy is stored in the gasket which is effective to insure the seal throughout the entire circumference.

An important feature of the invention is the cooperative relation between the size of the gasket and the shape of the groove. The groove includes an expansion chamber not normally occupied by the material of the gasket, but which permits the gasket to expand in the chamber as the latter is forced over the bead. When the concentric rings are locked together in sealing relation, the material of the gasket substantially fills the expansion chamber and energy stored in the gasket acts against the forward sloping surface of the bead and against the skirt of the inner ring to effect the seal. It will be noted that when the parts are locked together, the gasket has moved forwardly over the crest of the bead, yet it has not reached a position of freedom beyond the bead, being held in a still unrelieved condition against the forward slope of the bead by the engagement of the forward end of the outer ring against the flange on the inner ring. It will be understood that the use of material having smooth or low friction characteristics permits the employment of parts having a relatively tight fit, for the material of the container assists in lubricating the gasket ring over the critical dimension of the bead.

I claim:

1. A nursing unit comprising a relatively narrow collar formed for the attachment of a nursing nipple thereto and a relatively long container of thin, pliant, retractile material having an open end adapted to be secured to said collar, said collar comprising concentric inner and outer rings, said inner ring having a rearwardly extending skirt, the outer wall of said skirt having an annular sealing bead extending around the same intermediate the forward and rearward ends of said skirt, said outer ring having an inside wall of diameter slightly greater than that of said bead with an annular sealing gasket groove therein, an annular sealing gasket in said groove, the interior diameter of said gasket being less than the outside diameter of said bead, said outer ring being adapted to be pressed forwardly along said skirt to carry said gasket over said bead when the open end of a container is placed over the skirt, whereby to distort said gasket outwardly in said groove and to thereby seal the open end of the container against said skirt.

2. A nursing unit comprising a collar and a container of thin, pliant, retractile material having an open end adapted to be secured to said collar, said collar having a forwardly presented outlet with means for the attachment of a nipple thereto, said collar comprising inner and outer concentric rings, said inner ring having an outer surface with an annular bead thereon which rises to a crest and then drops inwardly toward said outer surface in a forward direction, the open end of said container being of such diameter as to snugly fit over said outer surface, said outer

ring having an inner surface of diameter slightly greater than that of said bead and having an annular sealing gasket housed in its said surface and protruding inwardly therefrom, the inner diameter of said gasket being slightly less than the outer diameter of said bead, said rings having cooperating abutment surfaces to limit forward movement of said outer ring over said inner ring and the open end of the container whereby to wedge said gasket against the forward portion of said bead beyond its crest.

3. A nursing unit comprising a collar and a container of thin, pliant, retractile material having an open end adapted to be secured to said collar, said collar having means for carrying a forwardly presented nursing nipple, said collar comprising inner and outer rings, said inner ring having an outer surface which rises forwardly in the form of an annular bead, said bead having a crest of maximum diameter and an annular area forwardly of said crest of reduced diameter greater than that of said outer surface, said outer ring having an inner surface of diameter greater than that of the crest of said bead and an annular gasket in said inner surface having an inner diameter less than that of the crest of said bead, and means for limiting the relative axial movement of said rings to retain said gasket in distorted condition beyond said crest but against said annular area to seal the open end of the container against said inner ring.

4. A nursing unit comprising a relatively narrow collar formed for the attachment of a nursing nipple thereto and a relatively long container of thin, pliant, retractile material having an open end adapted to be secured to said collar, said collar comprising concentric inner and outer rings adapted for relative axial movement with respect to one another, said inner ring having a rearwardly extending skirt constituting an inside sealing wall, said outer ring having an inner sealing surface constituting an outside sealing wall of somewhat greater diameter than that of said inside sealing wall, one of said walls having an annular sealing gasket groove therein, a unitary and removable annular sealing gasket of ring-like form and of rubber or the like in said groove, said groove being of such depth and having a sufficiently restricted opening to house said gasket against displacement therefrom upon relative movement of said rings, and said gasket being of greater diameter than the depth of said groove in order to normally protrude therefrom, the other of said walls having a cooperating annular sealing bead thereon of such diameter as to engage the protruding portion of said gasket upon passing the latter and to compress said gasket into said groove, said outer ring being adapted to be pressed relatively and axially along said skirt to carry said gasket over said bead when the open end of a container is placed over said skirt to distort said gasket into its groove and to thereby seal the open end of the container between said rings, said collar having means for limiting the relative movement of said rings in a position where said gasket has passed beyond the crest of said bead but remains in distorted pressure contact against that annular area of said other of said walls on the trailing side of said bead.

5. A construction in accordance with claim 4 wherein said groove includes an expansion chamber not normally occupied by the material of said gasket but which permits the gasket to expand therein as it is forced over said bead.

6. A construction in accordance with claim 4

wherein one side of said groove is recessed to form an expansion chamber not normally occupied by the material of said gasket but which permits said gasket to expand therein as it is forced relatively over said bead.

7. A construction in accordance with claim 4 wherein said container is made of a smooth film-like material having a relatively low coefficient of friction and wherein the relative diameters of said bead and the protruding portion of said gasket presented thereto are such as to require the lubricating action of the material of said con-

5 tainer to pass said gasket to sealing position beyond the crest of said bead.
